TEAR STRIP TYPE CONTAINER AND
RECLOSURE THEREFORJohn E. Socke, Pelham Manor, N. Y., assignor to
American Can Company, New York, N. Y., a
corporation of New Jersey

Application December 11, 1944, Serial No. 567,665

2 Claims. (Cl. 220—54)

1

The present invention relates to a metal tearing strip container or can having an interior collar arranged inside of the tearing strip and has particular reference to an improved construction of container of this type which has a lined reclosure cover within the sealed container having threaded engagement with the collar when enclosed within the can, such a cover being made effective for hermetically reclosing the opened container after removal of the tearing strip in opening the container.

An object of the present invention is the provision of an interior collar tearing strip can wherein a reclosure cover has threaded engagement with the collar and within the sealed can, the opening of the can by removal of the tearing strip releasing the reclosure cover for use in reclosing the can.

Another object of the invention is the provision of a hermetic air tight tearing strip can having a collar hermetically secured to the body wall, the collar providing a threaded seat for a reclosure cover confined completely within the can, such a cover being made effective for hermetically reclosing the opened can after the removal of the tearing strip in opening the same.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a tearing strip container embodying the present invention;

Fig. 2 is an enlarged sectional view taken substantially along the section lines 2—2, Fig. 1, and illustrating the can parts in their initial condition with a reclosure cover confined within the sealed can; and

Fig. 3 is a view similar to Fig. 2 but of the opened can after the tearing strip has been removed and the initial can cover has been discarded, the view showing the reclosure cover in its air-tight reclosing position.

The present invention embodies a container having a body 11 and end closures 12 secured thereto in double seams 13. The usual sealing gasket or compound lining 14 is used in the seams 13 to make the same hermetic.

An interior collar 15 is located inside of the body 11 adjacent the upper end of the body, adjoining collar and body beads 16, 17 (Fig. 2) being formed incident to such a connection. The collar and the body connection is also made as

2

an air-tight joint and for this purpose the body wall may be perforated by a row of perforations 18 extending along a central line horizontally of the body bead 11. Solder is afterwards sweated in to form an encircling seal by applying the molten solder from the exterior and flowing it through the perforations.

Above the beads 16, 17 the body wall 11 is scored with a pair of parallel score lines which include a lower score line 21 and an upper score line 22 setting off a tearing strip 23. At the side seam of the container, the tearing strip terminates in a tongue 24 which provides for engagement of the usual opening key. The two score lines 21, 22 preferably are cut on the interior wall of the body in the usual manner.

The collar 15 at the lower score line 21 is formed with an inwardly and upwardly extending double rounded corner 25 which merges into a vertical wall 26 spaced inwardly from the body wall 11 and of a smaller diameter. At the top the interior wall 26 terminates in an inwardly extending reclosure curl 27 which provides a smooth mouth for the opened container. The body wall 11 above the upper score line extends into the upper double seam 13, this portion of the body wall being designated by the numeral 31.

A reclosure cover 35 is contained within the can and is of such construction as to be lightly carried on the interior collar 15 when the can is sealed initially but is made usable as a reclosure member when the container is opened by removal of the tearing strip 23. This cover has a cylindrical skirt 36 which terminates in an outwardly extending edge curl 37 at the bottom. The diameter of the skirt 36 is greater than that of the collar wall 26 which it embraces.

At the top the skirt portion 36 merges into an annular arched channel or groove section 38 connecting by an integral rounded corner 41 with a depressed flat integral annulus 42 which at the inside merges into an inwardly and upwardly inclined conical wall 43. At the inside and at the top the conical wall 43 extends by a gently curved corner 44 into a central panel 45. Preferably the plane of the central panel 45 passes through the top of the arched section 38 so that the cover 35 constitutes in effect a flush cover. Cooperating threads 48, 49 are formed respectively in the collar wall 26 and in the cover skirt 36.

A sealing gasket 51 is disposed in the annular groove formed on the under side of the arched cover wall portion 38. At the time the can is ready to be initially closed by seaming of the top end 12, the reclosure cover is loosely applied to

the collar 15. The threads 48 and 49 are inter-engaged but the gasket 51 preferably just lightly engages the curl 27 of the collar, as shown in Fig. 2. The gasket 51 has to do with the reclosing of the opened container and this is only a carrying position. When the top cover is seamed onto the can and it is fully sealed (as in Fig. 2) there is no danger of the enclosed reclosure cover 35 becoming unscrewed even though it is only loosely applied as the cover 12 prevents such displacement.

Upon removal of the tearing strip 23, the top cover 12 together with the detached body wall 31 may be thrown away as no longer of service. The can then may be fully opened by unscrewing the reclosure cover 35. The opened container thereafter may be hermetically sealed as often as desired merely by threadedly engaging the cover and the collar threads and rotating the cover. By screwing down tightly, the gasket 51 is caused to press down against the collar curl 27 so that the curl becomes embedded in the gasket.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In an air-tight sheet metal container capable of air-tight reclosure, a container body having score lines defining a removable tearing strip for opening the container, end closures for sealing the opposite ends of said body, a collar located inside of said body and hermetically secured at its inner end thereto, the upper part of said collar being spaced inwardly from said tearing strip, said collar having an upper portion extending inwardly and thence upwardly to provide a cylindrical wall terminating at the top in a reclosure curl, a separate rotatable reclosure cover seated on said collar and disposed entirely within said container and said top end closure, said cover having a depending cylindrical skirt and an inwardly spaced annular reclosure gasket channel, a sealing gasket in said cover channel for engagement with said collar curl, and interengaging means on the cylindrical wall of said collar and on the cylindrical skirt of said reclosure

sure cover for drawing said reclosure cover into an air-tight seal with said collar by embedding said collar curl into said reclosure cover gasket, the removal of said tearing strip to open the container permitting the hermetic reclosing of the opened container by said reclosure cover.

2. In an air-tight sheet metal container capable of air-tight reclosure, a container body having score lines defining a removable tearing strip for opening the container, top and bottom end closures for sealing the opposite ends of said body, a collar located inside of said body adjacent said tearing strip and hermetically headed at its inner end into said body in an air-tight seal, said collar extending inwardly to provide a cylindrical wall terminating in a reclosure curl spaced inwardly from the body wall, a separate rotatable reclosure cover seated on said collar and entirely confined within the sealed container and disposed beneath said top end closure, said cover having a vertically disposed depending cylindrical wall fitting outside of the cylindrical wall of said collar, a sealing gasket in said reclosure cover in vertically disposed alignment with said collar curl, and cooperating threads in the cylindrical walls of said collar and said reclosure cover respectively, said threads being rendered operative by removal of said tearing strip and said top end closure to open the container, to form an air-tight seal between said reclosure cover and said collar by drawing the reclosure cover gasket tightly in embedded engagement against the reclosure curl of said collar, thereby again hermetically sealing the container for reclosure purposes.
